UNITED STATES PATENT OFFICE.

JOSEPH C. BRUNO, OF BUFFALO, NEW YORK.

CUTTING-TOOL HOLDER.

1,293,687.

Specification of Letters Patent. Patented Feb. 11, 1919.

Application filed March 15, 1917. Serial No. 154,946.

To all whom it may concern:

Be it known that I, JOSEPH C. BRUNO, a citizen of the United States, residing at Buffalo, in the county of Erie and State of New York, have invented certain new and useful Improvements in Cutting-Tool Holders, of which the following is a specification.

My invention relates to a cutting-tool holder, and more particularly to a tool for working out slots and other openings.

Owing to the construction of tool holders as now applied to shaping and similar machines, certain kinds of work will often times be encountered which requires the construction of special tools, which tools are necessarily forged to angular shapes and are of considerable lengths in order to bring the cutting portion of the tool at the desired point of the work while leaving sufficient room between the work and the tool head to allow said head and the ram carrying the same the necessary freedom in action; but such specially formed tools, owing to their length and angular shapes, are flexible and therefore unreliable since they cannot be depended upon to make a true cut, particularly for the reason that they have a propensity to vibrate and chatter while moving in contact with the work during their cutting strokes.

One of the objects of my invention is to eliminate the undesirable features of the tools last above referred to, and to construct a holder which will enable the operator of a shaping or similar machine to cut slots and perform other operations in or on work pieces, particularly die cutting operations, which tool holders of the present day constructions are not adapted for, except with the use of specially constructed tools having the objections above noted.

Another object of my invention is the provision of a tool holder wherein the cutting tool projects forwardly beyond any portion of the holder, or any portion of the machine to which the holder may be attached, so that a tool carried by said holder will reach points or parts of a work piece inaccessible to the tools of ordinary holders.

A further object of my invention is to provide a tool holder having means for conveniently securing a tool in place, which means also permits quick and ready removal of the tool from the holder.

A further object is to provide a tool holder

adapted to be attached to the pivoted apron of a shaping or similar machine and which is equipped with adjustable means to permit the pivoted apron to swing on its swivel head to a limited degree only during the idle or return stroke of said tool holder; the adjustability of said means permitting the tool holder to be attached to any form of shaping or similar machine without limitations in its functions.

A still further object of my invention is the provision of a tool holder which is simple, inexpensive, and highly efficient in the performance of all classes of work done on shaping and similar machines.

With the above and other objects in view, the invention consists in a tool holder having adjustable buffing means to limit the swinging movement thereof during its return or idle stroke.

It also consists in the provision of a holder wherein the tool extends forwardly beyond any portion of the holder or parts of the machine movable with the holder.

It further consists in the construction of a tool holder so arranged that it is particularly adapted for die cutting and the cutting of slots in work pieces, while retaining its effectiveness for cutting exposed surfaces of work pieces in the usual manner; and it further consists in the novel features of construction, and in the arrangement and combination of parts to be hereinafter described and particularly pointed out in the subjoined claims.

In the drawings,—

Figure 1 is a side elevation of a portion of a shaping machine showing a work piece in section clamped therein and the tool of my improved holder in the act of cutting a slot or machining a slot or opening within the work piece.

Fig. 2 is a front elevation of my improved tool holder detached from the machine with the cutting tool removed therefrom.

Fig. 3 is a section taken on line *a—a*, Fig. 2, with a tool clamped within the holder.

Fig. 4 is a section taken on line *b—b*, Fig. 2, with the lower and upper portions of the buffing device shown in elevation.

Fig. 5 is an enlarged horizontal section taken on line *c—c*, Fig. 1.

Fig. 6 is a transverse section taken on line *d—d*, Fig. 8.

Fig. 7 is a detached perspective view of a portion of the tool-clamping mechanism.

Fig. 8 is a vertical section taken on line *e*—*e*, Fig. 3.

Fig. 9 is an enlarged horizontal section taken on line *f*—*f*, Fig. 3.

5 Fig. 10 is a cross section taken on line *g*—*g*, Fig. 9.

Fig. 11 is a detached perspective view of one of the parts of the buffer head.

10 Fig. 12 is a detached perspective view of the buffer pin.

Reference being now had to the drawings in detail, the numeral 1 designates the standard or frame of a shaping machine, 2 the ram or tool carrying slide which is recti-

15 linearly movable in the usual manner, and 3 the work table having a portion 4 movable laterally and a portion 5 movable vertically.

6 designates the work holding jaws adjustable relatively in any common manner and 20 having a work piece 7 held therebetween, said work piece having a slot or opening 8 shown therein, representing one of many kinds of work for which this invention is particularly adapted.

25 Secured to the front end of the ram is the tool head 9 having the swivel head 10 secured thereto in the usual manner, said swivel head having the usual pivoted apron 11 attached thereto. This swivel head is 30 differently shaped in machines of different makes, but invariably the portion to which the apron 11 is pivoted projects forwardly from the segmental upper portion 12 of the swivel head.

35 The parts thus far described form no portion of my invention and are illustrated merely for the purpose of more clearly disclosing the operation and advantages of my improved holder.

40 My improved tool holder comprises a tool-holding member or body portion 13 which preferably has a wide parallel-sided upper portion 14 and a tapered lower portion 15. For convenience in securing the tool holder 45 to the pivoted apron of the swivel head, it is provided with a bolt hole 16 through which a bolt 17 is passed which threads into a flanged bushing 18 fitting into a counter-bored opening 19 formed in the pivoted apron, as best shown in Fig. 5, the enlarged portion of said opening being at the rear of said apron so that when the bolt 17 is threaded into said bushing the latter is drawn forwardly, the flange of said bushing serving as a stop and assuring a secure attachment of the body portion 13 of said holder to said pivoted apron. 20 is a washer fitting around the bolt 17 clamped between the head thereof and the front face of said body portion.

55 60 The tool holder is provided with an obliquely-disposed slot 21 arranged in its lower tapered portion, and in order that this slot be given greater depth than the thickness of the tool holder proper, a forwardly extending flange 22 is formed on the front face of

said body portion, the inner surfaces of said flange forming continuations of the walls of said slot through said body portion. Arranged within said slot is a tool clamping member 23, which by reason of the extension 70 of said slot through the holder is given considerable length and consequently considerable gripping surface. The lower end of said slot is rounded, as shown, and while the upper end thereof is shown rounded it may 75 be otherwise formed.

24 designates a cutting tool having a cylindrical shank 25 which fits into said slot, and bears against the lower rounded end thereof, and in order to effectively clamp 80 said shank, the lower end or edge of said clamping member 23 is provided with a longitudinal V-shaped groove 26 whereby two contact or bearing surfaces 27, 28, are provided; these contact or bearing surfaces being adapted to engage the cylindrical shank 85 of the cutting tool and clamp the latter firmly within said slot. This cutting tool may be flattened forward of said cylindrical shank, as at 29, and given any desired cutting edge, depending on the particular work 90 it is to perform. By thus arranging the tool receiving slot and the clamping member, the cutting tool extends forwardly, any desired distance, from the front face of the body portion 13, and the cutting tools may 95 be forged or otherwise worked from cylindrical bars, which are comparatively cheap and provide the tool with the required shank without resorting to machine work for producing the latter.

100 Extending obliquely through the body portion 13 on the line of said tool-receiving slot 21 is a bore 30, said bore extending from the upper end of said slot to the upper edge of the body portion and having its lower or inner extremity reduced in diameter, as at 31, to provide an upwardly facing shoulder 32. A push pin or rod 33 is entered in said bore 30 and has a free sliding 110 fit within the reduced portion 32 of said bore, the lower or inner end of said rod being threaded into the clamping member 23, as at 34. Said push pin or rod has an enlargement or head 37 at its upper end 115 against which one end of an expansion coil spring 35 bears, which spring surrounds said push pin and has its other end bearing against the shoulder 32. The upper end of the bore 30 is threaded and receives a set 120 screw 36 which bears against the upper face of the enlargement or head 37 of said push pin or rod.

125 As shown in Figs. 3 and 8, the set screw 36 has been screwed inwardly and has forced the push pin 33 and clamping member 23 downwardly, with the result that said clamping member has effectively clamped the shank of the cutting tool 29. In order to release said cutting tool it is simply nec- 130

essary to slightly unscrew the set screw 36, whereupon the coil spring 35 surrounding said push pin, acts to raise the latter and with it the clamping member. This will 5 permit the ready withdrawal of the tool from the holder. When the tool is removed from the holder, the clamping member is retained in position within the tool-receiving slot 21 with its V-shaped groove in receiving position, thus it is only necessary to insert the shank of the cutting tool into the lower end of the slot, and upon screwing the set screw downwardly the tool will again be clamped. I will now state, that owing to the 10 lower end of the tool-receiving slot being rounded and the lower edge of the clamping member being provided with a V-shaped groove, cutting tools having different sized cylindrical shanks may be clamped in position, and the arrangement provided also enables cutting tools having different shaped shanks to be used in connection with this improved holder.

During the forward or cutting movement 25 of the tool holder, the cutting tool is held in a rigid manner, and by reason of the tool being practically a straight member without angular portions, it is entirely free of vibrations.

30 During the return movement of a tool holder, it is necessary that the cutting edge of the tool passes idly over the surface of the work piece operated upon, and for this reason the tool holder of a shaping or similar machine is invariably attached to a pivoted apron, such as shown at 11, in the drawings; consequently the apron will swing forwardly on its pivot during such return stroke, and when operating the ram quickly, 35 this swinging movement creates considerable noise. Moreover, it is oftentimes found that the apron has not fully recovered itself when commencing the next forward cutting stroke and the work to be performed will therefore 40 be imperfect. To avoid this I have provided the body portion with a buffing device 38 which comprises an upstanding bar 39 having a reduced lower end 40 fitting into a socket 41 formed in the upper end of the 45 body portion 13 of the tool holder, said bar being secured within said socket by means of a set screw 42 threaded into a tapped opening 43 extending from said socket 41 outwardly to an enlarged opening or pocket 50 44, the outer end of said set screw terminating within said pocket so that it is entirely concealed, thus avoiding all projecting parts at this point.

55 Projections at the side edges of the tool holder are undesirable since they tend to interfere with proper and free working conditions.

The upper end of the bar 39 is slotted, as at 55, the lower portion of the slot being enlarged and of cylindrical formation, as at

46, and having a narrow slit 47 extending downwardly therefrom.

48 designates a bar or link, which is comparatively flat and the lower end of which enters the slot 45. The two jaws 49 at opposite sides of said slot therefore lie against opposite faces of said bar or link 48 and are firmly clamped against such faces by a bolt 50 which passes through openings in one of said jaws and in said link, and takes into a 70 threaded opening in the other jaw. By loosening said bolt, the bar or link 48 may be swung at any angle with reference to the bar 39, as indicated in Figs. 3 and 4.

A buffer head 51 is provided which has a 80 cylindrical body portion or cylinder 52 provided with a flat extension or lug 53 at one end and with internal screw threads 54 at its other end, said threads receiving the threaded inner end 55 of a buffer pin guide 85 56 which is tapered at its outer end and provided with an axial guide bore 57. A buffer pin 58 is slidable within said guide bore and has its outer end rounded, as at 59. The outer end of said buffer pin normally 90 projects beyond the outer end of said guide and its inner end is provided with a flat head 60 against which one end of a coil spring 61 bears; said spring being situated within said body portion or cylinder 52 and having its 95 other end bearing against the end wall 62 of said cylinder. Said spring therefore serves to hold said buffer pin in projected position.

The upper end of the link or pin 48 is 100 pivotally connected to the flat extension or lug 53 of the body portion or cylinder of said buffer head by a bolt 63 which passes through an opening in said bar or link and is threaded into an opening in said extension or lug. The bar or link 48 being pivotally connected to the upstanding bar 39 and to the buffer head enables said buffer head to be moved to different points with reference to the position of the body portion 13 of said tool holder; and said buffer head, 110 while intended to be retained in a horizontal position, may be arranged at an angle to the horizontal when it is found that the machine to which the tool holder is applied will not permit of its being retained in 115 horizontal position.

In Fig. 1 the buffer pin is shown in contact with the front face of the segment 12 on the swivel head 10, but it is apparent that said pin need not necessarily engage 120 this particular part of the shaping machine, as any other fixed point, whether fixed by adjustment or permanently fixed, may be so engaged.

125 During the return movement of the tool holder, during which the pivoted apron 11 swings forwardly or tends to swing forwardly, the spring 61 in the buffer head offers the necessary resistance to such action and allows only the slight movement 130

of the pivoted apron necessary to permit the tool to clear the work piece, the spring acting to immediately seat the pivoted apron when the return movement ceases; consequently the cutting tool is in the proper position for cutting immediately the forward or cutting movement commences.

My improved tool holder is susceptible of various changes in construction without departing from the spirit of my invention or sacrificing any of the advantages thereof, as will be clear from the scope of the appended claims.

Having thus described my invention, 15 what I claim is:—

1. A cutting-tool holder comprising a tool holding member, and a buffing device extending from said tool holding member and having a plurality of pivotally connected parts adjustable to different angles with respect to each other and a spring-pressed buffing member extending from one of said connected parts and adapted for engagement with a fixed part of the machine to which said cutting tool holder is secured.

2. A cutting-tool holder comprising a tool holding member, and a buffing device comprising a bar rigidly secured to said tool holding member, a link pivotally connected at one end with the outer end of said bar and a buffer head pivotally connected to the opposite end of said link.

3. A cutting-tool holder comprising a tool holding member, and a buffing device comprising a bar rigidly secured to said tool holding member, a link pivotally connected at one end with the outer end of said bar and a buffer head pivotally connected to the opposite end of said link, said buffer head having a spring-pressed pin extending therefrom to engage a fixed object.

4. A cutting-tool holder comprising a tool holding member, a buffing device extending upwardly from said tool holding member and composed of a rigid bar secured to said tool holding member, a link pivotally connected at its lower end to the upper end of said rigid bar, a cylinder pivotally connected to the upper end of said link, a spring within said cylinder, and a buffer pin extending from said cylinder and being retained in its projected position by said spring.

5. A cutting-tool holder comprising a tool holding member, and a buffing device comprising a plurality of connected members and a buffer head, said buffer head being capable of being retained in horizontal position and being adapted to bear against a fixed part of the machine to which said cutting-tool holder is secured.

6. A cutting-tool holder comprising a tool holding member, and a buffing device extending from said tool holding member and

having a buffer member at its extremity, said buffer member being adjustable so that it may be positioned at different heights with reference to the upper edge of said tool holding member.

7. A cutting-tool holder comprising a tool holding member, a rigid bar extending upwardly from said tool holding member and having a forked upper end, a link pivotally connected at one end to the forked upper end of said bar, and a buffer head pivotally connected to the upper end of said link, said buffer head having a spring-pressed buffer pin projecting therefrom.

8. A cutting-tool holder comprising a tool holding member, and a buffing device composed of a plurality of pivotally-connected members, one of said pivotally-connected members including a cylinder, a guide member threaded into one end of said cylinder, a buffer pin within said guide member and projecting from the outer end of the latter, and a spring between said buffer pin and the inner end wall of said cylinder.

9. A cutting-tool holder comprising a tool holding member having an upwardly opening socket and a laterally opening threaded bore provided with an unthreaded enlarged outer end portion, a bar fitting with its lower end into said socket, a set screw threaded into said threaded bore and bearing with its inner end against the lower end of said bar within said socket and terminating with its outer end within the enlarged outer end portion of said bore, a link pivotally connected to the upper end of said bar, and a buffer head pivotally connected to the upper end of said link.

10. A cutting-tool holder comprising a tool holding member, and a buffing device extending from said tool holding member and having a buffer pin at its extremity, said buffing device being adjustable to enable the contacting end of said buffer pin to be positioned in different horizontal planes.

11. A cutting-tool holder having a tool holding member provided with a tapered lower end and an obliquely disposed slot terminating with its lower end in close proximity to the lower end of said member, a clamping member movable within said slot between which and the lower end of said slot a tool is adapted to be held, and means for moving said clamping member into clamping position and retaining the same in said position.

12. In a cutting-tool holder, a tool holding member having a parallel-sided upper portion and a tapered lower portion, means for securing said member at a point between its upper and lower ends to the swinging apron of a shaping or other machine, said tool holding member having an obliquely-disposed slot therein, a clamping member within said slot, a pin secured to said clamp-

ing member and spring-pressed to move said clamping member out of clamping position, and means engaging said pin for moving the latter and said clamping member into 5 clamping position.

13. A cutting-tool holder comprising a tool holding member having a parallel-sided upper portion and a tapered lower portion provided with an obliquely-disposed 10 slot terminating in close proximity to the lower end of said tapered portion, said member having a bore extending from the upper end of said slot to the upper edge of said member and said bore having its lower 15 end diminished in diameter to provide an upwardly-facing shoulder, a clamping member within said slot, a pin secured to said clamping member and extending into said bore, said pin having an enlargement at its

upper end, a coil spring surrounding said 20 pin and bearing at its lower end against said upwardly-facing shoulder and at its upper end against the underside of the enlargement of said pin, and a set-screw threaded into the upper end of said bore and bearing against the upper side of said enlargement. 25

14. A cutting-tool holder comprising a tool holding member provided with an elongated slot and a flange extending forwardly therefrom entirely around said slot to increase the depth of said slot beyond the depth of the tool holding member, a tool 30 clamping member within said slot, and means for moving said clamping member 35 into clamping position.

In testimony whereof I affix my signature.
JOSEPH C. BRUNO.
